UNITED STATES PATENT OFFICE.

WILLIS H. SARGENT, OF ST. JOHNSBURY, VERMONT, ASSIGNOR TO THE
E. & T. FAIRBANKS & COMPANY, OF SAME PLACE.

DESIGN FOR A LEG-SUPPORT.

SPECIFICATION forming part of Design No. 24,086, dated March 5, 1895.

Application filed December 29, 1894. Serial No. 533,359. Term of patent 14 years.

To all whom it may concern:

Be it known that I, WILLIS H. SARGENT, a citizen of the United States, residing at St. Johnsbury, in the county of Caledonia, State 5 of Vermont, have invented a certain new and original Design for a Leg-Support, of which the following is a description, reference being had to the accompanying drawings and to the letters of reference marked thereon.

10 My invention relates to a new and original design for a leg support.

The invention is illustrated in the accompanying drawings, in which—

15 Figure 1 is a side elevation representing my design; and Fig. 2 is a view at right angles to Fig. 1.

The leg support consists of a pedestal B comprising a base formed of three short curved legs disposed to give a broad support.

20 Rising from the base and merging into a loop *a* at the bottom are three curved limbs *h*, at first forming quite a convex curve and then

extending in an oblique line, formed on a slight curve but nearly straight to the point *l*, where they converge, this converging point 25 being well above the region of highest strain. From this point *l* two limbs diverge to the point *c* when they curve toward each other uniting to form a loop *d*. Each arm *h* above the point *l* is provided with the ornamental 30 portion *e* and the enlarged portion *f*. Extending upward from the loop *d* are two ears *g*.

Having thus described my invention, what I claim, and desire to secure by Letters Patent, is—

35 The design for a leg support, substantially as shown and described.

In testimony whereof I affix my signature in presence of two witnesses.

WILLIS H. SARGENT.

Witnesses:

FRANK O. FRENCH,
KENNETH FAIRBANKS.
